UNITED STATES PATENT OFFICE.

WILLIAM J. REGAN, OF WILKINSBURG, AND WILLIAM KELSO, OF PITTSBURGH, PENNSYLVANIA, ASSIGNEES TO THE McCONWAY & TORLEY COMPANY, OF PITTSBURGH, PENNSYLVANIA, A CORPORATION OF PENNSYLVANIA.

CAR COUPLER.

Application filed July 24, 1925. Serial No. 45,908.

This invention relates to the construction of car couplers of the vertical plane type in which the knuckle is normally restrained from performing and uncoupling rotation by 5 means of a gravity actuated lock.

The primary object of the present invention is to produce a car coupler of rugged construction in which the knuckle locking means and the device for actuating the latter are so 10 formed that accidental unlocking of the coupler is prevented when the device is in service.

A further object of the invention is to provide simple and reliable means for maintaining the coupler lock in unlocked position while the knuckle is closed, thus enabling the knuckle to be subsequently opened at will.

Another object is to provide a coupler in 20 which the parts may be readily assembled and in which the elements of the mechanism cooperate with each other to ensure the proper operative relation of parts; and a still further object is to produce a coupler in 25 which the knuckle locking mechanism is well suited for operation by means of a lock actuating device projecting below the coupler, but which also may be operated by a lock lifter extending upwardly through the 30 coupler head.

A principal feature of the invention involves the combination of a coupler head, a knuckle rotatably mounted on said head, a lock for said knuckle, and a lifter for actuating said lock, the lifter constituting means for cooperating with the coupler head and lock so as to prevent the latter from accidentally moving to unlocked position and the lock being adapted when supported in 40 unlocked position by said lifter to swing over and be supported by the knuckle while the latter is in coupled relation, whereby subsequent opening of the knuckle may take place.

45 Another primary feature of the invention involves the combination of a coupler head, a knuckle rotatably mounted on said head, a lock for said knuckle, and a lifter for actuating said lock, the lock and lifter being capable of executing relative sliding and 50 swinging movements and the coupler head having a shoulder for cooperating with the lifter to prevent accidental unlocking of the lock, the lifter having a shoulder which ex-

tends under said shoulder of the coupler head when the parts are in locked position and being provided with a plurality of faces which normally cooperate with the lock and coupler head respectively so as to prevent the lifter from swinging in a direction enabling the lock to move accidentally towards unlocked position. 55

Another feature of the invention involves the combination of a coupler, a knuckle rotatably mounted on said head, a lock for said knuckle, and means for actuating the lock to cause it to assume unlocked position, said lock being adapted to tilt with respect to its actuating means so as to assume a position in which it is supported in unlocked relation to the knuckle of the coupler while the latter is closed, the lock being provided with a knuckle locking portion and with a lug projecting from said locking portion and extending downwardly below the latter, the said locking portion normally standing in the path of uncoupling movement of the tail of the knuckle, the said lug constituting guiding means for preventing the lock from 60 tilting toward the knuckle until after said locking portion has been moved to a position permitting said knuckle to open, and the tail of said knuckle being formed with a ledge upon which said lug is adapted to seat after 65 the tilting movement thereof. 70

A further feature of the invention consists in embodying in the coupler a knuckle opening lever which is rotatably mounted upon a pivot pin projection rigidly attached to the coupler head, the said head being formed with a portion which normally overlaps the said lever so as to prevent the latter from becoming disassociated from its pivot pin while the knuckle is in assembled relation to the head. 75

A still further feature resides in the combination of a coupler head, a knuckle rotatably mounted on said head, a lock for said knuckle, and a lock lifter for actuating said lock, the said lock being formed with a guiding projection adapted to overlap and cooperate with the inner end of the tail of the knuckle when the latter is closed, and the coupler head at a point above the tail of the knuckle having a guiding wall adapted to cooperate with the said projection so as to guide the lock during its unlocking movement, the said guiding wall being substan- 80 85 90 95 100 105

tially in vertical alinement with the end portion of the tail of the knuckle with which the said guiding projection cooperates.

Other features of the invention pertaining to advantageous relations and forms of parts will hereinafter appear and be particularly pointed out in the claims.

In the drawings chosen for the purpose of illustrating preferred embodiments of the invention,

Figure 1 is a view, partly in side elevation and partly in vertical section, of a coupler embodying our invention, the parts being shown in normal locked relation assembled for use with a release rigging arranged beneath the coupler.

Figure 2 is a view, partly in plan and partly in horizontal section, of a portion of the mechanism illustrated in Fig. 1.

Figure 3 is a transverse sectional view on the line 3—3, Fig. 2, the knuckle opener being shown in elevation.

Figure 4 is a detail view, partly in elevation and partly in vertical section, showing the relative position of the parts when the lifter has raised the lock to lock set position.

Figure 5 is a detail view, partly in section and partly in elevation, showing the locking block raised to extreme height to cause an uncoupling rotation of the knuckle.

Figure 6 is a detail view, partly in elevation and partly in vertical section, showing the position assumed by the parts when the lock lifter acts to arrest an accidental unlocking movement of the locking block.

Figure 7 is a detail sectional view on the line 7—7, Fig. 1.

Figure 8 is a detail sectional view on the line 8—8, Fig. 1, showing the lock and lifter in normal locked relation.

Figure 9 is a front elevational view showing a modified form of the invention wherein a bottom operating lock lifter is actuated by a lever pivotally mounted upon the knuckle side of the coupler head.

Figure 10 is a detail view, partly in elevation and partly in vertical section, showing a modified form of the invention employing a top operating lifter for actuating the lock, the parts being shown in normal locked relation.

Figure 11 is a detail view, partly in plan and partly in horizontal section, showing a modified form of the invention in which the lock down shoulder of the coupler body is formed as a separate element.

Figure 12 is a sectional view on the line 12—12, Fig. 11.

Figure 13 is a view, partly in elevation and partly in vertical section, of the modified construction shown in Figs. 11 and 12.

Figure 14 is a view corresponding to Fig. 12, but illustrating a further modification of the construction.

Figure 15 is a view corresponding to Fig.

1 but illustrating a modified form of locking block and a coupler head provided with a bollard.

Figure 16 is a detail view, partly in elevation and partly in vertical section, of the locking block shown in Fig. 15.

Figure 17 is a front elevation of a modified form of locking block.

Figure 18 is a plan view of the modified locking block.

In the drawings 1 is a coupler head, 2 the knuckle, and 3 is the knuckle pin by which the knuckle is pivotally connected to the coupler head in the usual manner. In the specific embodiment of the invention illustrated the stem or shank 4, forming a part of the coupler body, is integrally connected to the head portion 1 of said body.

Slidably mounted within the coupler head is a vertically movable lock 5 which normally projects across the path of movement of the tail of the knuckle 2 so as to lock said knuckle in closed or coupled position. The lock 5 is adapted to be moved to unlocked position either by a bottom operating lock lifter 6 or by a top operating lock lifter 7 (see Fig. 10). In either case the lock and the lifter associated therewith are operatively connected so as to be capable of relative sliding and pivotal movements. It is preferred to constitute such a connection by providing the lifter, 6 or 7 as the case may be, with oppositely disposed trunnions 8 which extend into trunnion guideways or recesses 9 of the lock, the said lock being formed with an upwardly and rearwardly opening slot 10 to receive the adjacent portion of the lifter. The upper ends of the trunnion guideways 9 are located above and forward of the center of gravity of the lock 5, with the result that, as shown in Fig. 4, the lock upon being raised to unlocked location swings or tilts with respect to the lock lifter and is supported on the tail of the knuckle in lock set position, thus permitting the knuckle to be subsequently opened.

To permit the lock 5 to swing to lock set position after having been raised, the upper portion 11 of the rear face of the lock is beveled or inclined; and for a similar purpose the front face of the lock at one side thereof is cut away or beveled, as at 12. To support the knuckle locking portion 13 of the lock in raised position permitting the tail of the knuckle 2 to pass thereunder, the lock 5 is formed with a downwardly projecting lug 14 constituting a lock set leg whose lower end is adapted to rest upon a lock set ledge or seat 15 on the upper surface of the tail of the knuckle at a point adjacent the lock 5. The ledge 15 extends only a part of the way along the rear upper edge of the tail of the knuckle and gradually diminishes or tapers in width so that as the knuckle 2 executes an opening move-

ment the lock set lug or projection 14 rides off the knuckle, thus allowing the lock to drop slightly so that the under surface of its knuckle locking portion 13 is supported upon the upper surface of the knuckle tail. It will be appreciated that the length of the ledge or lock set seat 14 on the tail of the knuckle governs the extent to which the knuckle can be opened before the lock is unseated from its lock set position.

The upper portion of the lug 14 projects laterally from the body of the lock 5 and overlaps the inner end of the tail of the knuckle (see Fig. 2) thus serving as a guide to prevent the lock from tilting forwardly until after the knuckle locking portion 13 of the lock has been raised sufficiently to permit the knuckle to open. Above the tail of the knuckle and in substantially vertical alignment with the inner end of the latter the head of the coupler is formed with a vertically extending wall 16 which is adapted to cooperate with the projection 14 on the lock so as to guide the latter during an extended unlocking movement.

Both the bottom operating lock lifter 6 and the top operating lock lifter 7 provide means for preventing accidental unlocking of the lock due to the shocks and jars incident to service. To perform this function of locking the lock in locked position both forms of lifter are provided with a shoulder 17 which extends under a lock down shoulder 18 of the coupler head or body when the lock 5 and its lifter are in locked relation. If, as shown in Fig. 6, the lock 5 should be accidentally jarred towards unlocked position while in service the lifter will be raised until its shoulder 17 comes into engagement with the lock down shoulder 18 of the coupler head, thus preventing further unlocking movement of the lock. To ensure very efficient and positive functioning of the means for preventing accidental unlocking of the lock, each form of lock lifter is provided with a vertically extending face or surface 19 which bears against the front face of the lock down wall or shoulder of the coupler head when the parts are in locked position; and each of the lifters is provided on its forward side with a vertically extending face or shoulder 20 which engages a corresponding face on the lock 5 when the coupler is locked, the faces or shoulders 19 and 20 being disposed on opposite sides of the horizontal plane passing through the axis of the trunnions 8. By cooperating with the coupler head and lock, respectively, these faces or shoulders 19 and 20 upon the lock lifter prevent said lifter from accidentally rotating in a direction which would cause its locking shoulder 17 to swing or move from beneath the cooperating lock down shoulder 18 of the coupler head. The lower end of the bottom operating lifter 6

is preferably provided with an eye or aperture 21 for receiving the end of an uncoupling lever or other suitable coupler release rigging mechanism. The top operating lock lifter 7 may advantageously be provided with an eye or opening 22 at its upper end for a like purpose.

The coupler is preferably provided with a bell crank knuckle opener lever 23 pivotally mounted upon a horizontally extending pivot pin 24 which is preferably secured to the coupler head by being cast in place therein. The longer arm of the knuckle opener extends downwardly behind the tail of the knuckle 2 so that when the lock 5 engages the shorter arm the knuckle opener is caused to rotate and thereby throw the knuckle to open position. For actuating the knuckle opener lever the lock is provided on its forward face with a projection or lug 25 which, when the lock is raised to perform an extended unlocking movement, engages the shorter arm of the knuckle opener lever, thereby forcing this member to rotate upon its pivot pin 24. For the purpose of preventing the knuckle opener lever 23 from becoming accidentally disconnected from its pivot pin 24, the coupler head may be advantageously provided with a retainer wall 26 which extends toward the knuckle opener lever and whose forward end lies substantially in the same transverse plane as the free end of the pivot pin 24. The retainer wall 26 is so disposed laterally with respect to the pivot pin 24 that the knuckle opener lever 23 cannot turn sufficiently far on said pivot to pass out of overlapping relation to said wall so long as the knuckle 2 is in assembled position. To permit the knuckle opener to be removed from its pivot pin it is first necessary to disconnect the knuckle from the coupler head. This allows the long arm of the knuckle opener to be rotated towards the lock sufficiently far to clear the retainer wall 26.

Means for preventing accidental closing of the knuckle 2 may be employed if desired. An advantageous and simple construction which may be adopted for this purpose consists of a coiled spring 27 which encircles the lower end of the knuckle pin 3, one end of said spring extending into a perforated lug 28 at the lower end of the pulling lugs of the knuckle and the other end similarly cooperating with a perforated lug 29 on the under side of the coupler head 1.

Figs. 1 and 3 illustrate the form of lever 30 preferably used for actuating the bottom lock lifter 6 when a low side pull uncoupling rod is to be used. This lever, which is of bell crank form, may be pivotally attached by a pin 31 to lugs 32 formed on the under side of the coupler head. One of its arms 33 enters the eye or aperture 21 in the lower end of the lifter 6, while its other arm is

formed with an eye 34 permitting attachment of a pull rod. Fig. 9 shows the style of lifter actuating lever 35 preferably employed for actuating the lifter 6 when a top 5 or high left side pull uncoupling rod is to be used. This lifter is pivotally mounted upon the coupler head by means of a pivot pin 36 passing through lugs 37 integral with said head. Its lower arm projects through 10 the eye 21 in the lifter so that when the lever is rotated by its pull rod the lifter 6 moves upwardly and causes the lock to perform an unlocking movement.

Figs. 11, 12, and 13 illustrate a modified 15 construction in which the lock down shoulder for cooperating with the lock lifter to prevent accidental unlocking of the lock is formed as a bar 38 which extends across the coupler barrel or shank 4 and is rigidly 20 secured to the latter by means of a pin or rivet 39. To permit this cross bar 38 to be placed in position one of the walls of the coupler shank is provided with a suitable opening 40. Opposite this opening the inner 25 face of the opposing wall of the coupler shank is formed with a socket or recess 41 for receiving the inner end of the bar 38.

The construction shown in Fig. 14 is substantially the same as that seen in Figs. 11, 30 12, and 13, except that the cross bar 38 is held in assembled position by a key member 42 which is bent so as to overlap the outer end of the cross bar after the latter has been placed in position. Other features of construction shown in Figs. 11 to 14, inclusive, 35 are identical with parts heretofore described and accordingly have been indicated by corresponding reference numerals.

Figs. 15 to 18, inclusive, show an embodiment of the invention in which the coupler head 1 is provided on its upper side with a bollard 43 for cooperating with a coupling link of the continental type. While the locking block 5 and bottom operating lock 45 lifter 6 heretofore described are preferably employed with this modified form of coupler head, a lock 44 of somewhat different form adapted for actuation only by a bottom operating lifter may be associated therewith if 50 desired. The lock 44 shown in this form of the invention has trunnion guideways or recesses 45 which are of slightly different shape from the trunnion guideways 9 of the lock 5 but, as in the case of the lock 5, the 55 upper ends of the guideways 45 are located above and forward of the center of gravity of the lock so as to enable the latter to tilt to lock set position. The lock 44 also differs from the lock 5 in that the rearwardly opening slot 46 for receiving the upper end of the lifter does not open through the upper surface of the lock. Except for the differences noted the modified form of construction shown in Figs. 15 to 18, inclusive, is 60 the same as that disclosed in Fig. 1, and

accordingly similar parts have been identified by corresponding reference numerals.

In assembling the coupler the knuckle opener lever 23 is first placed on its pivot pin 24. To do this the lower end of the long arm of the knuckle opener is swung toward the right or guard arm side of the coupler as far as the opening in the throat of the coupler head will permit. This brings the body of the knuckle opener to the right of the retainer wall 26 cast in the coupler head and thus permits the knuckle opener to be slipped over the end of its pivot pin 24. The lock lifter, 6 or 7, as the case may be, is then inserted in the head and the locking block entered through the throat opening in the forward face of the coupler head 1. The end of the lifter is then brought into assembled relation with the lock, and finally the knuckle 2 is placed in position and secured by the knuckle pin 3.

When the lock lifter is actuated to effect an unlocking operation of the lock, it first slides vertically upward with respect to said lock until the lower edge of its face 20 below the trunnions is on a line or above the adjacent wall of the recess in the locking block. At or about this time the upper sides of the trunnions 8 come into contact with the upper inclined walls of the trunnion guideways 9, and continued upward movement of the lifter will therefore cause its lock engaging end to recede into the recess 10 of the lock, thereby withdrawing the shoulder 17 of the lifter from beneath the lock down shoulder 18 of the coupler body and thus freeing the lock for an unlocking movement. If the unlocking movement of the lock effected by the lifter is extended only sufficiently far to unlock the knuckle, the lock upon reaching such unlocked position tilts upon the trunnions 8 of the lifter and assumes lock set position, as shown in Fig. 4, thus permitting the knuckle to be subsequently opened. If, however, as shown in Fig. 5, the lock moves upwardly sufficiently far to bring the lug 25 thereof into contact with the short arm of the rotatable knuckle opener lever 23, the knuckle opener lever is caused to rotate and its long arm by contacting with the tail of the knuckle swings the knuckle to open position.

A car coupler constructed in accordance with the invention is strong, simple, easily assembled and disassembled and performs the required operations with a high degree of reliability and efficiency.

We claim:

1. A car coupler involving a coupler head, a knuckle rotatably mounted on said head, a lock for said knuckle, and a lifter for actuating said lock, said lock and said lifter being operatively connected so as to be capable of relative sliding and swinging movements, said head being provided with a

shoulder adapted to be engaged by said lifter to thereby prevent accidental unlocking of said lock, said lifter being provided with a shoulder adapted to extend under said shoulder of the coupler head when the lock is in locked position and also being provided with a plurality of faces which, when said lifter is in normal locked relation to said lock, respectively cooperate with said lock and said coupler head to thereby prevent said lifter from swinging in a direction permitting its said shoulder to move from beneath the said cooperating shoulder of the coupler head, and said lock when moved to unlocked position by said lifter being adapted to swing with respect to said lifter so as to be supported in unlocked position on the tail of said knuckle while the latter is in closed position.

20 2. A car coupler involving a coupler head, a knuckle rotatably mounted on said head, a lock for said knuckle, and a lifter for actuating said lock, said lock being provided with a portion which is adapted to seat upon the tail of said knuckle to thereby maintain said lock in unlocked position while the knuckle is closed, said lifter being provided with trunnions forming means for slidably and rotatably connecting said lifter and said lock, said lock having a rearwardly opening slot for receiving a portion of said lifter and being formed with guideways for said trunnions extending forward of the center of gravity of said lock, said lifter having a shoulder which normally projects rearwardly beyond said lock when the latter is in locked position, said coupler head being provided with a shoulder adapted to extend over and be engaged by said shoulder of the lifter to prevent accidental unlocking of said lock, and said lifter being provided with a plurality of faces disposed above and below said trunnions and adapted respectively to cooperate with the coupler head and lock to thereby prevent said lifter from swinging in a direction permitting its said shoulder to move from beneath the said cooperating shoulder of the coupler head.

30 3. A car coupler involving a coupler head, a knuckle rotatably mounted on said head, a lock for said knuckle, and a lifter for actuating said lock, said lifter constituting means for preventing said lock from accidentally moving to unlocked position, said lifter and said lock being operatively connected so as to be capable of relative sliding and pivotal movements, and said lock being adapted when moved to unlocked position by said lifter to swing over and be supported by said knuckle while the latter is in closed position.

40 4. A car coupler involving a coupler head, a knuckle rotatably mounted on said head, a lock for said knuckle, and a lifter for actuating said lock, said lifter being slidably

and pivotally connected to said lock and extending downwardly therefrom through an opening in the coupler head, said lifter being adapted to cooperate with said lock and said head to prevent said lock from accidentally moving to unlocked position, and said lock when moved to unlocked position by said lifter being adapted to swing toward and be supported by said knuckle while the latter is in closed position.

5. A car coupler involving a coupler head, a knuckle rotatably mounted on said head, a lock for said knuckle, and means for moving said lock to unlocked position, said lock being adapted to tilt with respect to said means and comprising a knuckle locking portion and a guiding projection, said knuckle locking portion being adapted to stand in the path of uncoupling movement of the tail of the knuckle, and said guiding projection being adapted to overlap the inner end of the tail of the knuckle so as to prevent said lock from tilting forwardly until after said knuckle locking portion has assumed a position permitting said knuckle to open.

6. A car coupler involving a coupler head, a knuckle rotatably mounted on said head, a lock for said knuckle, and means for actuating said lock to cause it to assume unlocked position, said lock being adapted to tilt with respect to said means and comprising a knuckle locking portion and a lug projecting from said locking portion and extending downwardly below the latter, said locking portion being adapted to stand in the path of uncoupling movement of the tail of the knuckle, said lug constituting guiding means for preventing said lock from tilting toward said knuckle until after said locking portion has been moved to a position permitting said knuckle to open, and the tail of said knuckle being formed with a ledge upon which said lug is adapted to seat when the lock has tilted after being moved to unlocked position.

7. A car coupler involving a coupler head, a knuckle rotatably mounted on said head, a lock for said knuckle, and a lock lifter for actuating said lock, said lifter and lock being operably connected with capability of relative movement, said lock being formed with a knuckle locking portion and a guiding projection, said locking portion being adapted to stand in the path of uncoupling movement of the tail of the knuckle, said guiding projection being adapted to overlap and cooperate with the inner end of the tail of the knuckle when the latter is closed, and said head being provided above the tail of said knuckle with a guiding wall which is adapted to cooperate with said guiding projection, said guiding wall being substantially in vertical alignment with the said end portion of the tail of the knuckle with which said projection cooperates.

8. A car coupler involving a coupler head, a knuckle rotatably mounted on said head, a lock for said knuckle, a lifter for actuating said lock, and a rotatable lever for opening said knuckle, said lock and said lifter being operatively connected so as to be capable of relative sliding and swinging movements, said head being provided with a shoulder adapted to be engaged by said lifter to thereby prevent accidental unlocking of said lock, said lifter being provided with a shoulder adapted to extend under said shoulder of the coupler head when the lock is in locked position and also being provided with trunnions and with a plurality of faces disposed above and below said trunnions and adapted respectively to cooperate with the coupler head and lock to thereby prevent

said lifter from swinging in a direction permitting its said shoulder to move from beneath the said cooperating shoulder of the coupler head, said lock being formed with guideways for said trunnions, said guideways extending forward of the center of gravity of said lock, said lock when moved to unlocked position by said lifter being adapted to tilt so as to be supported in unlocked position on the tail of said knuckle while the latter is closed, and said lock being adapted upon an extended unlocking movement to engage and actuate said knuckle opening lever. 20 25 30

In testimony whereof we affix our signatures.

WILLIAM J. REGAN,
WILLIAM KELSO.
